F. M. Metzger

Attorney

UNITED STATES PATENT OFFICE.

GEORGE KUHNS, OF TEMPLE, OKLAHOMA.

WRENCH.

1,378,687.

Specification of Letters Patent. Patented May 17, 1921.

Application filed April 1, 1920. Serial No. 370,498.

To all whom it may concern:

Be it known that I, GEORGE KUHNS, a citizen of the United States of America, residing at Temple, in the county of Cotton 5 and State of Oklahoma, have invented new and useful Improvements in Wrenches, of which the following is a specification.

The object of the invention is to provide a comparatively simple and relatively inexpensive wrench for general pipe rod and nut 10 use wherein the jaw faces subjected to wear in operation may readily be interchanged or replaced without involving the loss of the body portion or main features of the structure, and furthermore to provide a construction 15 wherein the elements which are directly subjected to wear may be chilled or tempered to a higher degree of hardness without subjecting the other portions of the 20 tool to a similar treatment, and with these objects in view the invention consists in a construction and combination of parts of which a preferred embodiment is shown in the drawing, wherein:

25 Figure 1 is a side view of a wrench wherein the jaws are particularly adapted for use upon rods, pipes and similar round objects not fitted with angular wrench seats.

Fig. 2 is an edge view of the same.

30 Fig. 3 is a detail view in perspective of the jaw-holding end of the shank.

Fig. 4 is a similar view of the reversible fixed jaw.

35 Fig. 5 is a similar view of the movable jaw.

Fig. 6 is a like view of the bushing for the pivot bolt by which the jaws are secured to the shank.

In the construction illustrated the shank 40 or handle 10 is bifurcated at its inner end to form spaced ears 11 in which are formed registering bolt openings 12 for the reception of a transverse pivot bolt 13, and pivotally connected with the shank by means 45 of said bolt is a swinging or movable jaw 14 having a removable or replaceable serrated face 15 adapted for co-operation with the serrated faces 16 of a fixed jaw consisting of independent members 17 also secured 50 to the shank by means of the transverse bolt 13 and having in their inner faces seats or cavities 18 for the respective reception of the ears 11 formed by the bifurcation of the shank.

55 The seats or cavities 18 are designed to snugly fit the ears 11 so as to dispose the

inner surfaces of the body portions of the fixed jaw members 17 flush or in common planes with the inner surfaces respectively of the ears as indicated in Fig. 2, and the 60 openings 19 in said fixed jaw members being in registration with the openings 12 in the ears, a common bolt 13 serves to secure the said jaw members to the shank and also form a pivot for the movable or swinging 65 jaw, it being preferable, however, to dispose an annular bushing 20 upon the portion of the bolt between the inner surfaces of the ears 11 to fit in the relatively enlarged opening 21 provided in the pivotal end of said 70 swinging jaw.

The fixed jaw members are preferably provided with oppositely facing concaved engaging faces 16, in co-operation with either of which the serrated face of the 75 swinging jaw may act, it being obvious that the fixed jaw members are interchangeable with reference to the ears 11 to dispose either of their serrated faces in opposing relation with the swinging jaw, and furthermore that the swinging jaw is reversible 80 with relation to the shank so as to swing in either direction from the plane thereof. Obviously with this provision for interchanging or rearranging the jaw members, 85 it is possible to utilize to the fullest extent the gripping faces of the jaws, and moreover the face of the movable jaw may be renewed or replaced when worn without involving the renewal of the entire jaw structure. 90

In connection with the movable jaw it is preferable to employ an operating rod 22 provided with a stem 23 extending through a suitable perforation 24 in said jaw and operating in a guide eye 25 located at a convenient point on the shank, so that by the pressure of the thumb or a finger of the hand grasping the handle the swinging jaw may be moved into proper relation with the 100 opposing face of the fixed jaw to properly engage an interposed pipe or rod. In the construction illustrated the guide eye is formed upon a shank 26 extending through the handle and fitted with an adjustable 105 nut 27.

What is claimed is:

A wrench having its shank provided at one end with a bifurcation forming parallel spaced ears, fixed jaw members having oppositely directed concaved faces and also provided at their inner sides with cavities 110

or seats for receiving said ears, a common bolt extending through the ears and the fixed jaw members for securing the latter in operative relation with the handle, and a 5 pivotal jaw mounted upon said bolt in the interval between the spaced ears and having a concaved gripping face for opposing rela-

tion with the faces of the fixed jaw, a bushing being interposed between said bolt and the movable jaw.

In testimony whereof I affix my signature.

GEORGE KUHNS.
